C. G. NELSON

METALLIC WINDOW SASH

Filed March 7, 1925

Inventor

Charles G. Nelson.

FIG. 2.

By Owen, Owen & Crampton

Attorneys

UNITED STATES PATENT OFFICE.

CHARLES G. NELSON, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS.

METALLIC WINDOW SASH.

Application filed March 7, 1925. Serial No. 13,686.

To all whom it may concern:

Be it known that I, CHARLES G. NELSON, a citizen of the United States, and a resident of Chicago Heights, in the county of Cook and State of Illinois, have made an invention pertaining to a Metallic Window Sash, which invention is fully set forth in the following specification.

My invention relates to metallic window sashes and more particularly to means for preventing the tilting of an outside sash member.

The purpose of my invention is to improve the construction of the sash so that the various parts will maintain their proper positions. The nature and operation of my invention will more fully appear as the description proceeds.

In the accompanying drawings forming a part of this specification, Figure 1 is an elevation of a plate which I have added to the sash construction; Figs. 2 and 3 are sections of sash members showing this plate in use in combination with different forms of sashes.

The plate shown in Figure 1 comprises a sheet metal member originally of substantially rectangular shape, but having one end 10 somewhat narrower than the other end 11. An opening 12 is formed in the larger end of the plate. An offset 13 is formed midway in the length of the plate and flanges 14 are bent upward and downward on each side of the plate, so as to stiffen it and prevent transverse bending.

In Fig. 2 I have shown a member 15 interposed between an upper and lower window. The upper window has an inner sash supporting member 16. A cover plate 17 rests upon the member 15. A metallic plate 18 is positioned against the front of supporting member 16 and is provided with an outward flange 19. A member 20 is positioned between the flange 19 and the main body of plate 18. At the lower portion of support 16 the plate 18 is bent outward at 21 to receive the upturned flange 22 of cover plate

17, and the outer end of plate 18 is then bent outward so that it rests upon plate 17. Member 20 comprises a flange 24 that rests 50 against the vertical portion of plate 18 and terminates in an outwardly turned flange 25. A securing member 26 passes through flange 24 and the vertical portion of plate 18 and secures them in position against supporting member 16. 55

The glass plate 27 is held in place against flange 19 by an outer sash member 28, which has a flange 29 contacting the outer surface of the glass and a lower flange 30 resting 60 upon flange 23 of the back plate 18. Sash member 28 is drawn against the glass by means of a screw 31 which passes therethrough and through suitable openings in members 24 and 18 into the supporting mem- 65 ber 16.

The draw-plate, which constitutes the essential element of my invention, is attached to flange 30 of outer sash member 28 by a portion 32 of flange 30 projecting through 70 opening 12 and spread above the opening so as to rivet the plates together. The offset 13 is located at the end of flange 30 so that the narrower end of the draw-plate rests upon flange 23. Flanges 14 of the draw- 75 plate fit snugly beneath flange 25 at the lower edge of member 20 immediately beneath screw 31. This construction holds end 10 of the draw-plate down against flange 23 and prevents the upward tilting of flange 80 30 when screw 31 is driven home.

An inner sash-supporting member 33 is provided for the top of the lower window, and inner sash member 34 is secured in place against supporting member 33 and is held in 85 position by a stiffening member 35 having a flange 36 fastened by securing member 37 to supporting member 33. A glass plate 38 is held against the inner sash member by an outer sash member 39 having a flange 40 90 adapted to contact the glass and a flange 41 adapted to rest against the lower side of member 15. The outer sash member is held in place by a screw 42 passing through said

outer member and through an opening in flange 36 and into supporting member 33. The metal of flange 36 is bent outward in the form of a flange 43 to form an opening 6 for the passage of screw 42 and for a further purpose which will be described.

In this form of sash, the draw-plate is secured to flange 41 by a portion 44 of the metal of that flange being spun through opening 12 in the draw-plate. The draw-plate has its narrow end 10 positioned beneath flange 43, with flanges 14 of the draw-plate resting against flange 43, so that the inner end of the draw-plate is held firmly 15 against tilting downward when screw 42 is driven home, and in this manner the outer sash member 32 is prevented from tilting.

In Fig. 3 another form of sash construction is shown applied to the top of a window. The upper sash-supporting member 45 has therebeneath an inner supporting member 46. A sheet of glass 47 is held directly against the inner supporting member by an outer sash member 48, which has a flange 49 resting against the sheet of glass and a flange 50 positioned against member 45. The outer sash member is held in place by screw 51 passing through said member and into supporting member 46. The draw-plate in this construction is fastened to flange 50 by spinning through opening 12 a portion 52 of the metal of said flange. In this case the inner end of the draw-plate is prevented from tilting downward by being drawn against and biting into the wooden supporting member 46, as indicated at 53.

In each of the structures shown there is an offset portion 54 of the outer sash member adapted to receive outer end 11 of the draw-plate and hold it securely in position. Tilting of the outer sash member is prevented because one edge is drawn against the glass plate and the other edge is drawn directly against the end of the draw-plate; but even if the draw-plate should be a trifle short, the outer sash member could not tilt so as to raise its lower flange out of place, because that flange is held securely beneath the stiff draw-plate, which in turn, is held down at both ends.

As will be seen, I have provided a very simple construction of draw-plate which may be used in the various ways shown and in analogous ways to prevent the tilting of the outer sash member when it is drawn into place by the screw.

What I claim is:

1. In a window sash construction, a sash member having a flange along one edge adapted to contact a sheet of glass and a flange along the other edge perpendicular to the sheet, attaching means adapted to apply drawing force to said member midway between said flange to draw said member

towards the plane of the sheet, a draw-plate 65 having one end seated in a groove in said member and attached to the second said flange, and means to prevent the draw-plate from tilting relatively to the plane of the sheet.

2. In a window sash construction, a sash member having a flange along one edge adapted to contact a sheet of glass and a flange along the other edge perpendicular to the sheet, attaching means adapted to apply drawing force to said member midway between said flanges to draw said member towards the plane of the sheet, a sheet metal draw-plate having longitudinal stiffening 75 flanges and attached to the second said flange 80 of said member, and means to prevent the draw-plate from tilting relatively to the plane of the sheet of glass.

3. In a window sash construction, a supporting member substantially perpendicular 85 to the plane of the sheet of glass, a sash member having a flange along one edge adapted to contact the face of the sheet of glass and a flange along the other edge adapted to rest on said support, attaching 90 means adapted to apply drawing force to said member midway between said flanges to draw the member towards the plane of the sheet, a draw-plate having one end resting upon and attached to the second said 95 flange of said member and its other end offset so that it rests against said support, and means to prevent the draw-plate from tilting, relatively to the plane of the sheet.

4. In a window construction, a glass 100 sheet, a supporting member positioned across the plane of the sheet, a supporting member inside of the sheet, an outside sash member outside of the sheet and having one flange resting against the sheet and another 105 flange resting against the first said supporting member, an inside sash member between the sheet and the second said supporting member, a screw passing through said sash members into the second said supporting 110 member, and a draw plate in position to maintain the flange of the outside sash member in position against the first said supporting member.

5. A construction in accordance with claim 115 4, wherein the outer end of the draw-plate rests in a groove in said outside sash member.

6. A construction in accordance with claim 120 4, wherein the inner sash member is provided with a flange overlying the inner end of the draw-plate.

7. A construction in accordance with claim 125 4, wherein the inner sash member is provided with a flange in position to hold down the inner end of the draw-plate and in turn be held down by the screw.

8. A construction in accordance with claim

4 wherein an opening for the passage of longitudinal stiffening flanges along its screw through the inner sash member is formed by bending a portion of the metal of said member into a flange in position to rest 15 upon the inner end of the draw-plate.

9. In a metal sash construction, a draw-plate comprising a sheet of metal bent so that its ends extend in opposite directions in parallel planes.

10. 10. In a metal sash construction, a draw-plate comprising a sheet of metal having

11. In a metal sash construction, a draw-plate comprising a substantially rectangular sheet of metal bent so that its ends extend 15 in opposite directions in parallel planes and that longitudinal stiffening flanges are formed along its edges.

In testimony whereof, I have hereunto 20 signed my name to this specification.

CHARLES G. NELSON.
